UNITED STATES PATENT OFFICE.

HENRY C. BOWLUS, OF SPRINGFIELD, OHIO, ASSIGNOR TO ARTHUR D. HOSTERMAN, OF SPRINGFIELD, OHIO.

FLUSHING AND VENTILATING APPARATUS FOR CLOSETS.

Application filed May 7, 1925. Serial No. 28,575.

This invention relates to a flushing and ventilating apparatus for closets.

One object of the invention is to provide a simple efficient ventilating device which 5 can be quickly and easily installed.

A further object of the invention is to provide a seat controlled flushing mechanism which will be simple in construction and highly efficient in operation.

10 A further object of the invention is to provide such an apparatus in which the seat controlled actuating device for the flushing mechanism will be mounted on and within the ventilating conduit, thereby enabling the 15 flushing mechanism and its actuating device to be mounted in the proper relation to the closet without interfering with the ventilating device.

Other objects of the invention will appear 20 as the apparatus is described in detail.

In the accompanying drawings Fig. 1 is 25 a transverse sectional view taken through a ventilating shaft showing a plurality of closets connected therewith; Fig. 2 is a side elevation, partly broken away, of an apparatus embodying my invention; Fig. 3 is 30 a longitudinally vertical sectional view through the ventilating conduit and flushing valve mechanism; Fig. 4 is a horizontal longitudinal section taken through the ventilating conduit and showing the actuating 35 device for the flushing mechanism in plan and partly broken away; and Fig. 5 is a sectional detail view of the connection between the seat and the actuating devices.

In these drawings I have illustrated one embodiment of my invention and have shown the same in connection with a closet comprising a bowl 1 of a well known type. 40 Mounted on the top of the rear wall of the bowl is a ventilating conduit 2, the forward end of which is closed and the bottom wall of which is provided near its forward end with an opening 3 which overhangs the bowl and is in open communication therewith. The rear end of the conduit is connected with a suitable outlet. Usually the conduit extends through a wall, such as shown at 4, and is in open communication with a suction 45 chamber or ventilating shaft, as shown at 5 in Fig. 1. Preferably a suction fan is connected with this ventilating chamber or shaft to withdraw the air therefrom. The conduit 2 is preferably rectangular in cross section so that it can be mounted in an opening

in the wall made by removing the necessary bricks and with a comparatively small cutting away of masonry as compared with a round conduit for which a round opening must be made. The flat lower wall of the 60 conduit rests upon the upper edge of the rear wall of the bowl and is preferably secured thereto by screws extending through apertured lugs 2^a projecting from the opposite sides of the conduit and, if desired, suitable 65 packing material may be interposed between the conduit and the bowl to protect the porcelain.

Connected with the bowl is a flush pipe 6 which, in the present arrangement, is connected with the rear wall of the bowl near the top thereof and extends through the wall 4 of the ventilating chamber or shaft and is connected, by suitable valve mechanism 70 arranged within that chamber or shaft, with a source of water supply under pressure. In the apparatus here shown I have provided a storage receptacle or tank 7 in 75 which water may be stored under pressure and then discharged through the flush pipe to the bowl. To this end the tank 7 is connected with both the flush pipe 6 and with a supply pipe 8 which may lead to the city water main or any other suitable supply of 80 water under pressure. The connections between the tank and the supply pipe and between the tank and the flush pipe are automatically controlled by the position of a seat 9 which is supported above the bowl 85 and is movable with relation thereto. As 90 here shown, the tank 7 is connected with the supply pipe and the flush pipe through a single valve casing 10 which is provided at one end with a valve chamber 11 with which the supply pipe 8 is connected, and is 95 provided at its other end with a valve chamber 12 with which the flush pipe 6 is connected. Arranged between the chambers 11 and 12 is an intermediate chamber 13 with 100 which the tank 7 is connected by means of a pipe 14. The chamber 13 is separated from the chamber 11 by a partition 15 having a port 16 through which communication may be established between the two chambers. This port is controlled by a valve 17 slidably mounted in the chamber 11 and preferably provided with a contact portion 18 of rubber or other suitable yielding material which will establish a close contact with that 105 portion of the partition 15 which surrounds 110

the port 16 and constitutes the valve seat. Preferably the rubber contact member 18 is seated in a circular recess in the valve member so that the rubber is surrounded by a flange 19 which prevents the same from being flattened or distorted by its contact with the valve stem. The valve member 17 is also shown as having a skirt 20 of such a length that when the valve is in its closed position the skirt will extend across and close the opening leading to the supply pipe 8. This feature, however, is optional and is not essential to the operation of the device. The chamber 13 is separated from the valve chamber 12 by means of a partition 21 having a port 22 through which communication may be established between the two chambers. This port is controlled by a valve 23 which is preferably provided with a contact portion 24 of rubber or other yieldable material which will form a firm contact with that portion of the partition 21 surrounding the port 22 and constituting the valve seat, and this contact member is also surrounded by a flange 25 to prevent the same from being flattened or distorted by its contact with the valve seat. The two valves are so connected one to the other that when one is moved to its open position the other will be moved to its closed position and, in the present instance, both valves are rigidly secured to a valve rod 26 which extends through the ports 16 and 22 and is slidably mounted in a bearing 27 formed at the outer end of the valve chamber 12. It will be apparent that when the valves are in the position shown in Fig. 3 the tank is cut off from the supply pipe and is in open communication with the bowl. When the positions of the valves are reversed the tank will be cut off from the flush pipe and connected with the supply pipe and water entering the tank will compress the air contained within the tank so that the water will be stored in the tank under an air pressure equal to the pressure in the supply line. When the positions of the valves are again reversed the tank will be cut off from the supply pipe and connected with the flush pipe so that the water which has been stored in the tank will be discharged under pressure through the flush pipe to the bowl.

As has been stated this valve mechanism is preferably controlled by the position of the seat 9 and to this end I have mounted in the ventilating conduit 2 a transverse shaft 28, the side walls of the conduit being provided with bearings 29 in which the shaft is journaled. The shaft is provided at each end with a reduced portion 30 which projects beyond the adjacent side wall of the conduit and constitutes a pintle on which is journaled the bearing portion of a hinge 31 which is connected with and serves as a support for the seat 9. The seat is divided or

bifurcated at its rear end so as to extend on the opposite sides of the forward portion of the conduit and each side of the seat is provided with a hinge 31 and the two hinges are journaled on the respective pintles. The connection between the seat hinges and the shaft 28 is such that when the seat is moved in one direction rocking movement will be imparted to the shaft 28 and, as here shown, the end portions of the shaft 28 are provided with lugs 32 which are preferably arranged on opposite sides of the reduced portion or pintle 30 of the shaft. The hinge members are provided at their inner ends with lugs 33 arranged between the lugs 32 and held normally in contact therewith. In the present construction each of the lugs 33 is provided with a radial projection 33^a which overlaps the edge of the adjacent side wall and serves to limit the axial movement of said shaft.

The shaft 28 is provided between its ends and within the ventilating conduit 2 with a crank arm 34 which is here shown as a lug carried by a bolt 35 extending through the shaft and held therein by a nut 36. Pivotally connected with the crank arm 34 is an actuating rod 37, the opposite end of which is connected with the valve rod 26. In the present construction, this rod extends rearwardly through an opening or guideway formed in a transverse bar 38 mounted within the ventilating conduit and secured to the side walls thereof. I have shown this transverse bar as provided with rearwardly extending lugs 39 which are secured to the respective side walls of the conduit by means of screws 40. The rear end of the actuating rod, which extends beyond the guide bar 38 may be connected with the valve rod 26 in any suitable manner but, in the present instance, I have mounted on the end of the rod 26 a coupling member 41, which is preferably screw threaded onto the end of the rod and has at its rear end an opening of a relatively small size surrounded by a flange 42. Extending through the opening in the end of the coupling member is a screw 43 the head of which lies within the coupling member and contacts with the flange 42 while the threaded shank thereof is screwed into the end of the valve rod 26. Preferably the screw is not completely tightened down but sufficient looseness is left to permit of a slight pivotal movement of the coupling member and actuating rod with relation to the valve rod. A lock nut 41^a serves to retain the coupling member in adjusted positions. The actuating rod 37 is acted on by a spring which tends to move the same forwardly in a direction to seat the valve 17 and, as here shown, a spring 44 is coiled about the shaft 37 and bears at one end against the guide bar 38 and at its other end against an adjusting nut 45 which is

screw threaded onto the rod 37, and by means of which the tension of the spring may be regulated. In order that the length of the rod 37 may be varied I have shown the same as formed in two parts which are connected one to the other by a coupling member 46 in which the ends of the two rods are threaded. In order to retain the valve casing 10 in its proper relation to the 10 ventilating conduit and the actuating mechanism carried thereby I have interposed between the valve casing and the conduit spacing bars 47 which, in the present arrangement, have their forward ends secured to the 15 respective side walls of the conduit by means of the screws 40 and have their rear ends connected with the valve casing by means of screws 48. The arrangement of the lugs 32 and 33 on the shaft 28 of the seat hinges is 20 such that when the actuating rod is moved forwardly by the action of the spring 44 the lugs 32 on the shaft will engage the corresponding lugs 33 on the hinges and move the seat into a slightly elevated position, as 25 shown in the drawings. When the seat is depressed into contact with the top of the bowl the lugs 33 will act on the lugs 32 to rock the shaft 28 and move the actuating rod 37 rearwardly to unseat the valve 17 and to seat 30 the valve 23, thus permitting the storage tank 7 to fill. When the seat 9 is released the action of the spring on the rod 37 will elevate the seat and move the valve 17 to its closed position and the valve 23 to its 35 open position, thus permitting the water in the tank to be delivered to the bowl. It will be noted that the spacing arrangement of the lugs 32 on the shaft and the lugs 33 on the hinge members is such that the hinged 40 members may move relatively to the shaft to permit the seat to be moved to an upright position and across its center of gravity so that it will remain in that position. The rock arm 34 is arranged in a line 45 extending centrally between the lugs 32 so that it will properly control the position of the seat in the event the shaft 28 should be reversed or turned end for end.

The operation of the apparatus will be 50 readily understood from the foregoing description and it will be apparent that I have provided a very simple efficient apparatus for ventilating the bowl and for flushing the same. The apparatus is of such a character 55 that the flush pipe and the flushing mechanism may extend rearwardly from the center of the bowl and the flushing mechanism may be connected with the seat without in any way interfering with the installation 60 and operation of the ventilating conduit. Further, the arrangement is a very compact one and the conduit serves to conceal from view the larger portion of the seat controlled actuating device for the flushing 65 mechanism.

While I have shown and described one embodiment of my invention I wish it to be understood that I do not desire to be limited to the details thereof as various modifications may occur to a person skilled in the art. 70

Having now fully described my invention, what I claim as new and desire to secure by Letters Patent, is:

1. In a device of the character described, a bowl, a flush pipe connected with said bowl, valve mechanism to control the flow of water through said flush pipe, a ventilating conduit mounted at the top of said bowl in open communication therewith and having its rear end connected with an outlet, a shaft rotatably mounted in the walls of said conduit and extending beyond said walls, an arm connected with said shaft, an actuating rod arranged within said conduit, connected at one end with said arm and connected at its 75 other end with said valve mechanism, a spring acting on said rod to move the same in one direction, a seat, and hinge members for said seat mounted on the respective ends of said shaft for rotatory movement with relation thereto, said hinge members and said ends of said shaft having cooperating parts to cause said seat to be partially elevated by the action of said spring and to cause said actuating rod to be moved against the tension of said spring by the movement of said seat in one direction but permit said seat to be moved in the other direction independently of said shaft. 90

2. In a device of the character described, a bowl, a flush pipe connected with said bowl, valve mechanism to control the flow of water through said flush pipe, a ventilating conduit mounted at the top of said bowl in open communication therewith and having 100 its rear end connected with an outlet, a shaft rotatably mounted in the walls of said conduit and extending beyond said walls, an arm connected with said shaft, an actuating rod arranged within said conduit, connected 105 at one end with said arm and connected at its other end with said valve mechanism, a spring acting on said rod to move the same in one direction, a seat, and hinge members for said seat mounted on the respective ends of said shaft for rotatory movement with 110 relation thereto, said shaft and said hinge members having cooperating lugs so arranged that the movement of the shaft by said spring will cause said lugs to elevate the seat and the downward movement of the seat will cause said lugs to impart movement to said rod against the action of said spring, said lugs being so arranged with relation one to the other that said seat may 115 be moved relatively to said shaft into an upright position. 120

3. In a device of the character described, a bowl, a flush pipe connected with said bowl, valve mechanism to control the flow 125

- 4 of water through said flush pipe, a ventilating conduit mounted at the top of said bowl in open communication therewith and having its rear end connected with an outlet, a shaft journalized in the side walls of said conduit and having portions of reduced diameter extending beyond the respective side walls, an arm connected with said shaft within said conduit, an actuating rod extending lengthwise of said conduit, connected at one end with said arm and connected at its other end with said valve mechanism, a spring acting on said actuating rod to move the same in one direction, a seat, and 15 hinges for said seat journalized on the respective end portions of said shaft, said shaft and said hinges having cooperating lugs so arranged that the movement of said shaft in one direction by said spring will cause said 20 lugs to elevate said seat and the downward movement of said seat will cause said lugs to move said shaft and said actuating rod in the opposite direction against the tension of said spring, said lugs being so arranged with relation one to the other that said seat may be moved relatively to said shaft into an upright position.
4. In an apparatus of the character described, a bowl, a flush pipe connected with 30 said bowl, valve mechanism to control the flow of water from said flush pipe and comprising a valve casing mounted independently of said bowl, a ventilating conduit mounted at the top of said bowl and in open 35 communication therewith and having its rear end connected with an outlet, an actuating device mounted in said conduit and operatively connected with said valve mechanism, a seat movably supported on said bowl 40 and operatively connected with said actuating device, and means for connecting the valve casing with said conduit to maintain said valve casing in proper relation to said actuating device.
5. In an apparatus of the character described, a bowl, a flush pipe connected with 45 said bowl, valve mechanism to control the flow of water from said flush pipe and comprising a valve casing, a ventilating conduit mounted at the top of said bowl and in open 50 communication therewith and having its rear end connected with an outlet, a shaft mounted in the side walls of said conduit, an arm connected with said shaft within 55 said conduit, an actuating rod extending lengthwise of said conduit, connected at one end with said arm and connected at its other end with said valve mechanism, a spring tending to move said rod in one direction, a 60 seat pivotally supported above said bowl and operatively connected with said shaft to move said rod against the tension of said spring, and spacing bars connecting said conduit with said valve casing to maintain 65 said valve casing in proper position with relation to said actuating rod.
6. In an apparatus of the character described, a bowl, a flush pipe connected with 70 said bowl, valve mechanism to control the flow of water through said flush pipe and comprising a valve casing, a ventilating conduit mounted at the top of said bowl and in open communication therewith and having its rear end connected with an outlet, a shaft mounted in the side walls of said conduit, an arm connected with said shaft within 75 said conduit, an actuating rod extending lengthwise of said conduit, connected at one end with said arm and connected at its other end with said valve mechanism, a spring tending to move said rod in one direction, a seat pivotally supported above 80 said bowl and operatively connected with said shaft to move said rod against the tension of said spring, a guide bar extending transversely to said conduit, having lugs arranged adjacent to the respective walls thereof and having an opening in which said actuating rod is slidably mounted, screws to secure said lugs to the respective side walls, a spacing bar secured to said conduit by one of said screws and connected at its other end with said valve casing.
7. In an apparatus of the character described, the combination with a bowl, and a seat pivotally supported above the same, of a storage receptacle for water under pressure, a valve casing supported independently of said bowl and comprising an intermediate chamber connected with said storage receptacle and end chambers adapted to communicate with said intermediate chamber, a supply pipe connected with one of said end chambers, a flush pipe to connect the other of said end chambers with said bowl, valves to control the communication between said intermediate chamber and the respective end chambers, a valve rod on which said valves are mounted, an actuating rod supported on said bowl, means for pivotally connecting said actuating rod with said valve rod, a spring acting on said valve rod to move the same in one direction, and means for connecting said actuating rod with said pivoted seat, whereby the movement of said seat in one direction will move said actuating rod against the action of said spring.
8. In an apparatus of the character described, the combination with a bowl, and a seat pivotally supported above the same, of a storage receptacle for water under pressure, a valve casing supported independently of said bowl and comprising an intermediate chamber connected with said storage receptacle and end chambers adapted to communicate with said intermediate chamber, a supply pipe connected with one of 90 95 100 105 110 115 120 125

said end chambers, a flush pipe to connect the other of said end chambers with said bowl, valves to control the communication between said intermediate chamber and the 5 respective end chambers, a valve rod on which said valves are mounted, an actuating rod supported by said bowl and operatively connected with said valve rod, a spring acting on said actuating rod to move the same 10 in one direction, means for connecting said actuating rod with said pivoted seat to cause said rod to be moved against the action of said spring by the movement of said seat in one direction, and means for varying the 15 length of said actuating rod.

9. In an apparatus, of the character described, the combination with a bowl, and a seat pivotally supported above the same, of a storage receptacle for water under pressure, a valve casing supported independently 20 of said bowl and comprising an intermediate chamber connected with said bowl and end chambers adapted to communicate with said intermediate chamber, a supply pipe connected with one of said end chambers, a flush pipe to connect the other of said end chambers with said bowl, valves to control the communication between said intermediate chamber and the respective end chambers, 25 a valve rod on which said valves are mounted, an actuating rod supported by said bowl, a coupling member screw threaded onto one end of said actuating rod and having an opening in the other end thereof, a screw 30 extending through said opening and threaded into the end of said valve rod, a spring acting on said actuating rod, and an operative connection between said actuating rod and said pivoted seat.

40 10. In an apparatus of the character described, a bowl, a flush pipe connected with said bowl, valve mechanism to control the

flow of water through said flush pipe, a ventilating conduit mounted at the top of said bowl in open communication therewith and 45 having its rear end connected with an outlet, an actuating rod slidably mounted in said conduit and operatively connected with said valve mechanism, a spring acting on said actuating rod to move the same in one direction, a shaft journaled in the walls of said conduit, a rock arm carried by said shaft and connected with said actuating rod, said shaft having end portions projecting beyond the respective side walls of said conduit, 50 each of said end portions being provided with a lug, a hinged member journaled on each end portion of said shaft and having a lug to cooperate with the lug on said shaft, the lugs on said hinge members having 55 projections overlapping the adjacent walls of said conduit, means to retain said hinge member on the end portion of said shaft, and a seat supported by said hinge members.

11. In a device of the character described, 60 a bowl, a flush pipe connected with said bowl, valve mechanism to control the flow of water through said flush pipe, a ventilating conduit mounted at the top of said bowl in open communication therewith and having 65 parallel side walls extending rearwardly and adapted to be connected with an outlet, said side walls having aligned bearings near the forward end of said conduit, an actuating device operatively connected 70 with said valve mechanism and comprising a rock shaft journaled in the walls of said conduit, and a pivoted seat arranged above said bowl and operatively connected 75 with said rock shaft.

In testimony whereof, I affix my signature hereto.

HENRY C. BOWLUS.
